UNITED STATES PATENT OFFICE.

DAVID M. MCFARLAND, OF WEST CHESTER, PENNSYLVANIA, ASSIGNOR TO ATLAS POWDER COMPANY, OF WILMINGTON, DELAWARE, A CORPORATION OF DELAWARE.

METHOD FOR TESTING BLASTING MACHINES.

Application filed November 7, 1924. Serial No. 748,378.

To all whom it may concern:

Be it known that DAVID M. MCFARLAND, citizen of the United States, residing at West Chester, in the county of Chester and 5 State of Pennsylvania, has invented certain new and useful Improvements in Methods for Testing Blasting Machines, of which the following is a specification.

My invention relates to improvements in 10 devices used to determine the capacity of electrical blasting machines. The object of the invention is to render it possible to provide any desired factor of safety in the rating of a blasting machine.

15 It is common practice to detonate high explosives by the use of electric blasting caps. These electric blasting caps are detonated by passing a current of electricity through a resistance wire, or "bridge" inside 20 the cap. The bridge heats up when an electric current is passed through it. The hot bridge ignites some combustible, readily ignited substance in the cap, causing it to detonate. It is necessary to heat the 25 "bridge" to a temperature sufficiently high to ignite the mixture in the cap.

A certain minimum of electric current is required to fire a given kind of electric blasting cap. In order to make sure that the 30 cap will fire, an excess of electrical current should be applied.

It is common practice to rate electrical blasting machines by the number of caps connected in series, which the machine can 35 fire. This number can be determined by connecting various numbers of caps in series, and attempting to explode the caps with a blasting machine.

The above method is time consuming and 40 wasteful of caps. It has been the practice in the past, to substitute for all but one cap in the series, a resistance equivalent to that of all but one of the caps in the series. If the one cap used in series with the resistance 45 fires, it is assumed that the blasting machine can actually fire the number of caps equivalent to the resistance, plus one cap. This method gives the blasting machine an insufficient factor of safety, and at times, a 50 blasting machine will not actually fire the number of caps indicated by this test.

According to my invention, I connect a fixed resistance in parallel with the one

blasting cap used for the test. By adjusting the value of the fixed resistance which is shunted about the cap, any factor of safety may be secured. If the resistance of the shunt is equal to that of the cap, then half the current will flow through the resistance, and half through the cap. If the current is sufficient to fire the cap, then we know that the blasting machine is furnishing twice the amount of current necessary to fire a single electric blasting cap through an added resistance used in series equivalent to 65 that of the number of electric blasting caps for which it is desired to test the machine. For successful series firing it is necessary to have at least twice the current which will fire a single electric blasting cap. 70

I do not wish to limit myself to the method of varying the amount of resistance which is connected in series with the test cap and the blasting machine. My invention relates to the use of a fixed resistance 75 connected in parallel with the test cap, and in series with a variable resistance.

In the accompanying diagrammatic drawing, 5 designates the blasting machine, the capacity of which is to be tested. The terminals 6 and 7 of this machine are connected by conductors 8 and 9 to the terminals 10 and 11 of the testing instrument. The latter comprises a circuit in which a variable resistance 12 and a fixed resistance 80 85 13 are included. A blasting cap 14 is connected by wires 15 and 16 to the terminals of the fixed resistance.

If it be desired to test the blasting machine to determine, for example, whether it 90 has sufficient capacity to fire sixty electric blasting caps, the variable resistance 12 is adjusted until it is equivalent to the resistance of fifty-nine electric blasting caps and the lead wires of the blasting cap 14 are 95 connected to the ends of the fixed resistance 13. When the blasting machine 5 is operated the current will pass through conductor 8; that portion of the variable resistance indicated at 12^a and conductor 17. 100 Then part of the current will go through the resistance 13 and part through the blasting cap circuit 15, 14 and 16 and back to the blasting machine through conductor 9. If the resistance of the shunt 13 is made 105 equal to that of the cap circuit 15, 14 and

16, equal amounts of current will go through the fixed resistance and the cap circuit.

By making the resistance 13 of some other value than that stated, the ratio of the current passing through the cap circuit to that passing through the fixed resistance, can be changed.

It is to be understood that the invention is not limited to the precise arrangement set forth but that it includes within its purview whatever changes fairly come within either the terms or the spirit of the appended claim.

Having described my invention what I claim is:

The herein described method of testing and rating blasting machines which consists of arranging a variable resistance and a blasting cap in series with the blasting machine and shunting a fixed resistance of determined value across a portion of the circuit which includes only the blasting cap.

In testimony whereof he affixes his signature.

DAVID M. McFARLAND.
